UNITED STATES PATENT OFFICE.

LINFORD S. STILES, OF BROOKLYN, NEW YORK.

WATER-GAS APPARATUS.

Application filed August 18, 1921. Serial No. 493,246.

To all whom it may concern:

Be it known that I, LINFORD S. STILES, a citizen of the United States, and a resident of Brooklyn, county of Kings, and State of New York, have invented an Improvement in Water-Gas Apparatus, of which the following is a specification.

The object of my invention is to provide an improved construction and mode of operation of water gas apparatus with the purpose of increasing the output with a given size of apparatus, and especially in those cases where the gas is to be used for heating purposes alone or where a reduction in the oil required for a candle power unit is reduced in producing and supplying gas on a B. t. u. basis. By elimination of a portion of the oil heretofore employed, a very material reduction in the volume of gas results consequently to maintain the maximum output with a reasonable thermal unit value from a given apparatus under the reduced use of oil in association with the water gas, it becomes necessary to change or modify the internal construction of the parts heretofore constituting the carburetter and the superheater or fixing chamber, with a corresponding modification in the process. The making of these changes, hereinafter described, is done with the special purpose of increasing the output efficiency of the apparatus in respect to the carburetted water gas of the lower B. t. u. standard and enable it to be done with the same general gas apparatus heretofore in common use supplemented by modifications therein.

More particularly, it is my purpose to eliminate the employment of a separate carburetting chamber as heretofore used in relation to a superheating chamber, in the former of which the oil has been sprayed for carburetting the water gas received from the generator, and wherein the gas, after passing in a downward direction, has been caused to pass into the bottom of the superheating chamber and thence upward therethrough for fixation before being delivered through the wash-box to the gas main. In lieu thereof, I convert the carburetter and superheater chambers into a single chamber, into the bottom of which the water gas from the generator is delivered and which in gaseous form passes upward part way through the fixation chamber and thereat supplied with oil in the form of spray, which being gasified, passes upward through the remain-

ing portion of the fixation chamber and is delivered to the water seal box and mains, I thereby more greatly reduce the resistance to the expansion and passage of the gas than has heretofore occurred. The result of this improvement is, that a heavy oil may be employed with satisfactory gas production and a greater volume of gas from the oil produced with less objectionable carbon deposit and clogging of the checker brick work in the fixation chamber. A greater output of gas is thus insured from a given quantity of material; and in addition thereto, the periods of gas production between necessary cleaning and repairing of the checker work in the fixation chamber is considerably increased, thereby providing additional economy in the operation of the plant.

More especially, the object of my invention is to provide a water gas generating plant with a combined carburetter and superheating or fixing chamber containing suitable checker brick work through which the gases pass in an upward direction in their travel from the generator to the escape flue or outlet and wash-box, the said combined carburetter and fixing chamber being provided with means for admitting a spray of oil thereinto at a point intermediate of the upper and lower portions of the checker brick thereof; the operation being such that if the oil so injected, is not all instantly vaporized (which is liable to occur with heavy oils), the unvaporized oil in passing downward by gravity, is ultimately vaporized by contact with the checker brick in the lower portion of the carburetter and fixing chamber and by the hot water gas rising therethrough. In this manner the hydrocarbon gases both combined and free thus associated with the water gas are carried upward through the upper checker brick work, wherein the vaporized oil is fixed into a substantially permanent gas before passing from the apparatus. More generically stated, my invention comprehends means in a water gas generating apparatus for producing and causing the "blue gas" to pass in an upward direction through a superheating and fixing means such as heated checker brick work, combined with means for providing oil spray at a point intermediate of the upper and lower portions of the said superheating and fixing means, whereby the vaporized portions of the oil spray pass upward with the "blue gas" and the unvapor-

ized portions of the spray pass downward in a contrary direction to the "blue gas" until thoroughly vaporized; and whereby further the oil gas, produced by said downward process is thereafter caused to travel in the reverse or upward direction in association with the "blue gas."

The invention also embodies the method of generating carburetted water gas which 0 consists in the injection of heavy oil in the form of spray into the "blue gas" during its passage in contact with highly heated surfaces, and said injection of the oil made at a point intermediate of the upper and 5 lower levels of the heating means through which the "blue gas" passes, whereby heavy portions of the oil as are not readily vaporized when brought into contact with the heated water gas are caused to fall, by 10 gravity, in the reverse direction to the upward travel of the "blue gas" and be heated by the same in the presence of the heating means to vaporize said heavy oil portions, and thereafter causing the vaporized heavy 15 oil portions associated with the "blue gas" to rise through and become fixed in the upper level of the heating means.

With the above and other objects in view, the nature of which will be more fully understood from the description hereinafter, 20 taken in connection with the drawings, the invention consists in the novel construction of gas producing apparatus and mode of operation of the process conducted therein, 25 as hereinafter more fully described and defined in the claim.

Referring to the drawings: Fig. 1 is a 30 sectional elevation of a gas apparatus embodying my improvements and adapted for the practice of my improved process; and Fig. 2 is a modification of the same also adapted for the practice of the process.

Referring more particularly to the structure shown in Fig. 1, 2 is the generator or 40 "blue gas" producer, and is preferably arranged at the lower part of a tall sheet metal casing within the upper part of which is arranged a combustion chamber 16 and a combined carburetter and fixing chamber 50 15. By suitable flues and valves, the gaseous products from the generator during its blowing up process may be supplied to the combustion chamber and the heat produced thereby passed upward for heating the interior checkered brick work of the combined carburetter and fixing chamber, for highly heating it, whereas the water gas (blue gas) produced in the generator may be supplied to the same combustion chamber wherein 60 it is mixed with sprayed oil and the mixture then passed upward through the combined carburetter and fixing chamber and thence to the wash-box on its way to the holder.

65 The generator 2 may be of any ordinary

construction, being provided with a grate 3, ash pit 4, and charging doors or flues 5 near the top through which coal may be supplied. Air blast is supplied to the ash pit 4 by a blast pipe 6 and controlled by a valve 7. 70 Gas may be taken off on the "up run" from the upper end of the generator by a flue 9 having a control valve 11 and on the "down run" by the flue 12 having a control valve 14, said flue opening from the ash pit. The 75 generator is further provided with a steam pipe 8 opening below the grate 3 and discharging into the ash pit during the "up run" and is also provided with a steam pipe 8' discharging into the upper part of the 80 generator during the "down run". During the generation of the water or "blue gas", whether on the "up run" or "down run", the blast from pipe 6 is shut off, and steam from either pipe 8 or 8' admitted, as the case may be; but when heating up, the steam is shut off and blast turned on and the producer gas so provided is conveyed upward and carried off by flue 9. The general construction and mode of operation of the generator 85 is well known and will need no further explanation.

Referring more in detail to the construction of the combined carburetter and fixing chamber 15, the same is greater in cubical 90 capacity and cross sectional area compared to the cross sectional area of the generator chamber than what has heretofore been the combined cubical capacity of both the carburetter and the fixing chamber relative to 95 the generator capacity, so that there is far less resistance to the flow of both the heating gas and the carburetted water gas through the combined carburetter and fixing chamber than was heretofore the case where the gas was required to flow first through the carburetter and then through 100 the fixing chamber. The interior of the combined carburetter and fixing chamber is 105 filled with checker brick work such as indicated at 17 and 17^a, the former supported upon and above a perforated arch 22^b and the latter supported upon and extending from and above the perforated arch 18 at the bottom and terminating at a distance 110 somewhat below the arch 22^b, so as to leave a carburetting chamber 21^b thereat, said chamber provided with oil spraying nozzles 20. The checker brick work filling is diagrammatically illustrated as to its top and lower 115 portions in each case by way of locating its position. The upper checker brick work terminates below the top or crown of the fixation chamber so as to provide a secondary superheating chamber 19 having an escape flue 25 provided with a cover or valve 26 which is employed to close the said escape flue when the carburetted water gas is required to pass through flue 24, and washbox or seal 27 to the gas conduit 28 by which 120 125 130

the gas is conveyed to the holder. The perforated arch 18 constitutes a crown or roof to a combustion chamber 16 into which the gases from the generator are delivered by 5 flues 10. The perforated arch 22^b likewise constitutes a crown or roof to the carbureting chamber 21^b.

The flue 9 from the upper part of the generator 2 opens into the flue 10 through 10 the valve 11; and similarly flue 12 from the bottom of the generator is also connected with the flue 10 by an L-shaped flue 13, the flow therethrough being controlled by the valve 14. The latter flues 12 and 13 15 convey water or "blue gas" alone to the flues 10 leading into the combustion chamber 16, whereas flue 9 opening from the upper part of the generator conveys all products of combustion when the generator 20 is being blown for bringing its contents to incandescence and at other times conveys the water or "blue gas" alone.

The combustion chamber 16 is provided with a blast pipe 23 which receives air from 25 main 21 under pressure and which is controlled by a valve 22, the air thus supplied being employed with the products of combustion which pass from the generator at the time it is being blown, for raising its 30 contents to incandescence, the combustion taking place in the chamber 16 and providing heated products which pass through the perforated arch 18 and into the combined carburetter and fixing chamber and 35 therein employed for raising its temperature. The carburetting chamber 21^b is provided with one or more oil spray nozzles 20, whereby when the blast is shut off and the "blue gas" is supplied from the generator 2, the same is intermingled with the oil spray in the heated chamber, the oil being 40 vaporized and intimately associated with the "blue gas" to carburet it, with the result of increasing the available heat units 45 of the gas product, as a whole; and in this condition, said gases pass upward through the carburetter and fixing chamber of the shell 15 expanding therewith and rising therethrough at a speed which enables the 50 thorough carburetting of the "blue gas" and the final fixing of the same.

The upper part of the combined carburetter and fixing chamber, and heretofore designated as a superheating chamber 19, is provided with a blast pipe 23^a having communication, by a pipe 21^a, with the compressed air main 21, the supply of air from said pipe 21^a into the chamber 19, being controlled by a valve 22^a. By means of this blast pipe 23^a, the products of combustion employed in heating up the combined carburetter and fixing chamber may be supplied with additional air before they escape from the escape flue 25 during the heating up process, and in this manner insure a rela-

tively high, superheating temperature within the said chamber portion 19 and thereby enable it to provide additional heat as a final means of fixation of the carburetted gas at a time when the said blast is shut off. 70

It will be understood that in the operation of the apparatus just described, the resistance to the flow of the gases, both heating gas and carburetted water gas, through the combined carburetter and fixing chamber, 75 is considerably less than the same exists in the modern types of water gas apparatus wherein the carburetter and the fixing chamber are operated in series, and for this reason, the quantity of gases, whether produced 80 when blowing up the generator, or when generating water gas therein, are considerably increased in volume, during the normal operation of the apparatus, over what they were formerly in a modern gas apparatus of the same size; and consequently a greater output of gas in cubic feet is obtained with the apparatus constructed as herein set out, in a given period of time and 85 with the same coal consumption, than has 90 heretofore been possible wherein the carburetters and fixing chambers have been employed to operate in succession.

In a gas apparatus of the general arrangement of Fig. 1, so far as relates to the position of the generator below the carburetting and fixing chamber means, the construction thereof is similar to the Williamson type of gas apparatus embodied, for example, in the apparatus set out in Letters 95 Patent No. 767,217, dated August 9, 1904, to Eustace; and when the same is to be converted into a gas system embodying my improvements, the dividing wall heretofore 100 used in the chamber 15 as a separation between the carburetter and fixing chambers is removed, thereby materially increasing the available cross section of the combined carburetting and fixing chamber; and among other changes, the oil is supplied in 105 the chamber 21^b below the arch 22^b instead of at the top and within a chambered portion in the top of the carburetter, and further, the gas pipe or flue from flues 10 to the chamber 19 of the carburetter is removed and the gases of all characters supplied to the chamber 16 below the arch 18 and caused to pass upwardly through the same and the checker brick of the combined carburetter and fixing chamber. In this 110 way, the Williamson or Eustace type of apparatus may be readily changed to enable the more modern apparatus to be improved to meet the requirements of my invention and increase its efficiency in quantity production. 115

Where floor space is available, my improved apparatus may be so constructed 120 that the generator, and the combined carburetter and fixing chamber may be ar- 125

langed on independent foundations on the same level, as shown in Fig. 2. In this construction, the generator 2 is in all material respects the same as in Fig. 1, though the coal may be charged through a central top charging passage 5 provided with suitable covering or valve means. Similar numerals as reference designations are employed in Fig. 2 for corresponding parts shown in Fig. 1. The combined carburetter and fixing chamber 15 is similar in respect to the corresponding portions shown in Fig. 1.

In view of the fact that the combined carburetter and fixing chamber 15 sets upon a foundation on the same level with the generator and the products of combustion and gas are to be delivered from the generator in the chamber 16 at the bottom thereof, connection is made with the upper gas outlet of the generator 2 by a downwardly extending pipe or flue 13, which is in communication with the chamber 16 by means of a horizontal flue 10 and which, with flue 13, is in communication with the lower part of the generator by a flue 12 containing the valve 14. The valves 11 and 14 of the outlet flues of the generator 2 are employed alternately and correspond to the similar valves shown in Fig. 1. In Fig. 2, the oil spray is supplied by a spray pipe 20 into the carburetting chamber 21^b below arch 22^b, as in the case of Fig. 1, which carburetting chamber acts as a highly heated oil vaporizing space wherein the oil vapor is intimately mixed with the water gas passing from the generator and before passing upwardly through the upper portion 17 of the combined carburetter and fixing chamber. The oil spray delivered into the chamber 21^b will be partly vaporized and a portion will fall by gravity upon the lower checker brick work 17^a and become therein vaporized, the vapor so produced rising with the up flowing "blue gas" and passing through the carburetting chamber 21^b, arch 22 and the upper checker brick on its way to chamber 19 and outlet 24. As will be seen, the checker brick work 17 above the chamber 21^b in which the oil spray is injected, is greatly more in quantity and heating capacity than the checker brick work 17^a below said oil receiving chamber, and this is as it should be, as the quantity of the heavy hydrocarbons difficult of volatilization is relatively much smaller than those hydrocarbons of quality which are readily gasified and instantly pass upward from the chamber 21^b with the blue gas. Therefore, as the checker brick 17 is not only required to vaporize the lighter oils but also fix the gas embodying the same as well as those arising from the heavier hydrocarbons, the quantity of said checker brick work should be correspondingly greater than the brick work 17^a. The combustion chamber 16 is also provided with an air pipe 21 having a control valve 22, said air pipe supplying air blast to the combustion chamber 16 as in the case of Fig. 1. The upper part of the combined carburetter and fixing chamber is provided with an outlet chimney flue 25 which is controlled by a valve or cover 26, the latter being open during combustion of the gases and their upward passage through the chamber 15 for the purpose of heating it, but closed when the carburetted water gas is passing through the carburetter and fixing chamber. The carburetted water gas from the upper chamber 19 passes by pipe 24 into the wash-box or seal 27 and from there it flows through a pipe 28 and is conveyed to the holder or other apparatus, such as the scrubbers, as may be required. In a general way, if the combined carburetter and fixing chamber of Fig. 2 were placed on top of the generator 2, maintaining the connections 10 and 13 as shown, we would have a very similar construction to that shown in Fig. 1.

In all cases, there is a unitary highly heated chamber performing simultaneously the combined functions of carburetter and fixing chamber, the same being provided with checker brick work of usual construction and having a cross sectional area or passage greatly in excess of what has heretofore been the cross sectional area of either the carburetter or fixing chamber where the said chambers were connected in series, as is customary in the commercial forms of water gas apparatus. By this construction, the shape of the chamber is maintained circular and is, therefore, best suited for thorough utilization of the checker brick work and with the greatest production of carburetted gas with a given size of carburetting and fixing chamber, whereby a maximum output may be obtained. The construction furthermore provides one in which the first function, namely, carburetting, is performed upon the "blue gas" to the fullest extent required, and thereafter the second function, namely, the fixing of the gas, takes place during the further continuous passage of the carburetted gas through the checker brick work, it being understood that the lower portion of the checker brick work performs the special function in heating the "blue gas" preliminary to its meeting the oil vapor and in vaporizing any of the oil which has not been gasified in the chamber 21^b, this special function in connection with a carburetting and fixing chamber not having been heretofore employed, as far as I am aware. By performing the two functions, carburetting and fixing, in one chamber, they automatically take place in accordance with requirements, that is to say, the function of the fixing chamber wherein the gases

all pass in the same direction there is a tendency of a uniformity in the flow of gases through the carbureter and fixing chamber and thereby unaffected by reverse changes in the direction of flow and the consequent variation in pressures resulting therefrom.

When I refer to the chamber 16 as the combustion chamber at the base of the combined carbureter and fixing chamber, I do not wish to be limited thereby to any specific character of compartment or chamber to include under such designation any suitable space in which the gaseous products may 10 mingle with the blast to provide the heating gases for the checker brick work, though ordinarily, this chamber will be formed as a shallow compartment having a perforated arched roof upon which the checker brick 15 work is supported.

It will now be apparent that I have devised a novel and useful construction which embodies the features of advantage enumerated as desirable, and while I have in the 20 present instance shown and described the preferred embodiment thereof which has been found in practice to give satisfactory and reliable results, it is to be understood that I do not restrict myself to the details, 25 as the same are susceptible of modification 30 in various particulars without departing from the spirit or scope of the invention.

Having now described my invention, what I claim as new and desire to secure by Letters Patent is:—

A water gas apparatus, comprising a generator for generating water gas, an upright combined carbureter and fixer, a combustion chamber in the lower part of the combined carbureter and fixer in communication with the generator, a superheating chamber in the upper part of the combined carbureter and fixer, said superheating chamber having a valve controlled escape flue for waste products of combustion and a 40 separate outlet for the water gas, blast pipes with separate means of control opening 45 separately into the combustion chamber and the superheating chamber for supplying air for primary and final combustion within the 50 chambers during the heating up process, said carbureter and fixer being provided intermediate of its upper and lower chambers with checker brick work and an oil vaporizing chamber intermediate of the upper and 55 lower portions of said checker brick work, means for supplying oil to the oil vaporizing chamber, and a wash box in communication with the water gas outlet from the upper superheating chamber for permitting the 60 passage of the gases to be collected.

In testimony of which invention, I hereunto set my hand.

LINFORD S. STILES.
